(57) **CLAIM**

The ornamental design for a wheeled lane blocker and merchandise display stand, as shown and described.

DESCRIPTION

FIG. 1 is a perspective view of a wheeled lane blocker and merchandising display stand showing the new design;

FIG. 2 is a perspective view of the wheeled lane blocker and merchandising display stand of FIG. 1 absent the merchandising trays;

FIG. 3 is a right side elevational view of FIG. 2, the left side elevation is a mirror image of the right side elevation;

FIG. 4 is a front elevational view of FIG. 2;

FIG. 5 is a back elevational view of FIG. 2;

FIG. 6 is a top plan view of FIG. 2; and,

FIG. 7 is a bottom view of FIG. 2.

Those elements that are shown in the above drawings in phantom lines which include the merchandising trays and the stepped shelf do not form a part of the claimed design.
